UNITED STATES PATENT OFFICE.

EDWARD B. WICKS, OF SALT LAKE CITY, UTAH TERRITORY.

DESIGN FOR A PEN-WIPER.

SPECIFICATION forming part of Design No. 23,575, dated August 21, 1894.

Application filed June 26, 1894. Serial No. 515,789. Term of patent 14 years.

To all whom it may concern:

Be it known that I, EDWARD B. WICKS, a citizen of the United States, residing at Salt Lake City, in the county of Salt Lake and Territory of Utah, have invented and produced a new and original Design for Pen-Wipers, of which the following is a specification.

Reference is to be had to the accompanying drawings, forming a part of this specification, in which—

Figure 1 is an end elevation of a pen-wiper embodying my new design; and Fig. 2 is a side elevation of the same.

The leading feature of the design consists ¹⁵ in the novel configuration of the wiper as shown.

The wiper presents a circular figure as seen in side view and is ribbed as seen in edge view. ²⁰

I claim—

The design for a pen-wiper herein shown and described.

EDWARD B. WICKS.
